BUILDING FRAME UNIT

William E. Coffey, Excelsior, Minn., assignor, by direct and mesne assignments, to Contemporary Structures, Inc., Excelsior, Minn., a corporation of Minnesota
Filed Sept. 16, 1954, Ser. No. 456,549
3 Claims. (Cl. 20—5)

This invention relates to building construction and more particularly to a building frame unit.

In contemporary type architecture, there has been a growing tendency for simplicity in the design of dwelling and small building construction. For example, rustic-type single-story houses are often constructed so that the underside of the roof member constitutes the ceiling of the inner structure.

Also, partitions defining room structure are often constructed so as to be light and non-loadbearing. In some instances the partitions are so constructed as to be shiftable to alter the character of the building.

Construction of contemporary buildings of this type requires a flat and low roof and therefore the building frame must necessarily be strong enough to support the roof together with additional load such as snow which may collect thereon, and be strong enough to withstand additional forces such as high winds. The usual outside wall structure comprises wooden stud members 2" x 4" in cross-section and placed edgewise and vertically at 16 or 24 inches apart. The top and bottom ends of the stud members are usually tied together with upper and lower plates, the plates furnishing fastening means to secure the wall structure together with the foundation and with the roof structure. Window and door openings are framed into the walls during construction. Once the wall frame has been secured in position upon the foundation, the remainder of the building may be constructed in a number of different ways. The roof frame in the conventional structure of the class described is usually made up of roof rafters spaced apart the same distance as the wall studs and compressively supported by the walls and by partitions constructed within the building. Outer sheathing is nailed to the flat outer edge of the wall studs and outer covering such as siding may then be secured to the sheathing. Similarly, roof boards, decking, shingles and other roof materials may be secured at the upper edge of the roof rafters. The floor is constructed of joists and may be worked into the wall structure with the outer ends of the floor joists supported on the wall plates, or the floor may be first formed with the floor joists directly on the foundation and the outer wall structure secured peripherally on the floor structure.

The standard construction above described in all events pre-supposes a complete wall structure attached to, but not rigidly stressed with, the floor and foundation at the lower edges of the wall, and attached to but not rigidly stressed with the ceiling or roof joists and the wall partitions. In other words, the conventional frame structure pre-supposes practically all the stress on the wall and partition structures in the form of compression. The lateral stability of such frame structure is obtained through corner connections between joining walls and partitions and by virtue of internal bracing of the separate wall, floor and roof elements.

It is within the contemplation of this invention and an important object thereof, to provide a framing unit which, when incorporated in a building structure, will efficiently and economically provide strength and rigidity throughout its peripheral length for the mutual support of floor, wall and roof members.

It is a further object of the invention to provide a frame unit which will have self-contained rafter, stud and

2

joist qualities for defining peripheral support for all sides of a building and which can be rigidly tied together in horizontally spaced relation.

It is a still further object of the invention to provide a plurality of building frame units, each having provision for receiving horizontal ribbands in rigid connection and in planar relation with the edges of said units, to which can be directly fastened wall panels or sheets.

It is a still further object of the invention to provide unitary frame members for building construction of the class described which will simplify and cheapen the construction of such buildings while providing a pleasing appearance and a rugged long-lasting structure.

These and other objects and advantages of the invention will more fully appear from the following description made in connection with the accompanying drawings, wherein like reference characters refer to the same or similar parts throughout the several views, and in which:

20 FIG. 1 is a perspective view of the end section of a frame construction embodying my invention, the section showing an intermediate frame unit and an end unit with the horizontal braces and a representative number of roof and floor boards in position; the remainder of the structure is cut away to better show the cooperation of the parts; and

FIG. 2 is an exploded view of the building frame unit, all the parts being separated for clarity but maintaining their relative positions as they appear in the rigid and complete unit.

With continued reference to the drawing, the truss rafter is indicated generally at 10 and is shown in structural relationship to the other members in a housing construction in FIG. 1 and in individual parts in FIG. 2.

35 The truss rafter comprises a plurality of elongated rectilinear boards which are secured together in a special way to provide internal strength in the truss rafter itself as well as in conjunction with the other members of the frame. The several portions of the truss rafter are outer

40 boards 11 and 12 which abut at slightly angulated ends 13 and 14 respectively to form the peak portion of a roof, the pitch ordinarily being maintained at a low rate for the type of structure shown. The outer ends of the respective boards 11 and 12 may be cut angularly at 15

45 and 16 respectively, the ends extending outwardly to overhang the side walls. A similar pair of outside members 17 and 18 are provided and likewise have the same end pieces cut in the same manner so as to duplicate the first mentioned pair of members 11 and 12. An inner

50 elongated board 19 has the same width at its flat side as that of the members 11 and 17 and is adapted to be glued in laminated relation by such common wood gluing medium as resorcinol glue. The ends of the board 19 fall short of the corresponding ends 13 and 15 of boards 11

55 and 17, the most central end 20 lying usually a matter of a foot or so from end 13, and the outer end 21 terminating at the inner surface of the wall structure. A gap 22 is created between the end 21 of board 19 and the end 23 of the filler piece 24 which in turn has an outer end

60 25 which registers with the outer end 15 of board 11. Another inner board 26 may be identically laminated between the outer truss rafter members 12 and 18 with the end filler 27 similarly positioned so as to produce the gap 28 at the other side of the truss rafter.

65 A special collar joist 29 is adapted to interfit between the angular peak formed at the juncture of edges 13 and 14 on all four of the members 11, 12, 17 and 18, the collar joist having upper edges 30 and 31 which lie in the same plane with the respective top edges of boards 11,

70 17, 19 and 24 at one side, and with boards 12, 18, 26 and 27 at the other side. The end edges of the collar joist 29 are arranged so that edge 32 will abut against edge

20 of the intermediate board 19, and edge 33 will abut against the corresponding end 20 of the intermediate board 26. The lower edge 34 of collar joist 29 is formed in offset relation with respect to the lower edges of all of the other truss rafter boards, the collar joist then taking a reinforcing position with the edge 34 appearing below the peak in a web-like relationship with the other elongated and rectilinear members of the truss rafter as shown more clearly in FIG. 1. All of the members comprising the truss rafter are intended to be rigidly glued together and may, in addition, have other fastening means such as bolts 35, but these fastening means are not essential to the operation of the truss rafter if the members are properly adhered with a good quality of glue.

The bottom portion of my frame unit is the floor joist which is indicated generally at 36 and may simply comprise several rectilinear boards such as the outer members 37 at one side, the outer members 38 at the other side and the intermediate members 39 of corresponding dimension interposed in laminated relation with the outer members. These floor joist members may be made of shorter length boards, especially where the span is in excess of 8 or 10 feet, and it is only necessary in such case that the abutting positions typified by 40 between the members 37 and 41 between the members 38, be in staggered relation with respect to the abutting position 42 of the intermediate members 39, all as set forth in FIGS. 1 and 2. In order to obtain a better interfitting relation with other portions of the frame as will be presently described, it is preferred that the intermediate board members 39 be cut of such a length that the ends 43 will fall short of the ends 44 of the respective outer members 37 and 38. The recessed area formed by the offset relationship between ends 43 with respective and corresponding ends 44 is of a predetermined amount so as to permit snug interlocking of the interconnecting members which complete the frame unit.

The remaining members for completing the frame unit are the pair of stud members indicated generally at 45, one each being mountable at a side of the frame unit as shown in FIGS. 1 and 2. The stud member comprises a vertical rectilinear board, preferably an ordinary 2 x 4 board 46, having an upper end 47 which is cut at the same angle as the upper edge of truss rafter boards 11, 17 and 19, and the lower end 48 of which is cut square to correspond with the lowermost edge of the unit at the floor joist. The board 46 has at least one outer member laminated thereto, and preferably two, one at each side as shown at 49 and 50. The outside laminations of the stud 45 are preferably formed of 2 x 6 stock with the outer edges 51 and 52 respectively lying in the same plane with each other and adapted to lie in the same plane as the end edges 44 of the members 37 and 38 in the floor joist construction. The members 49 and 50 are laminated in adhering relation with the 2 x 4 member 46, the respective upper edges 53 and 54 being adapted to abut against the under edge of the outer members 11 and 17 in the truss rafter 10 while the intermediate board 46 has its upper end 47 extending in close-fitting relation in the gap 22 and in abutting relation with ends 21 and 23 of respective boards 19 and 24. The stud member 45 may be glued at all contacting surfaces with the truss rafter 10, but it is preferred that the projecting end of the board 46 which terminates in the upper edge 47, be bolted through the outer members 11 and 17 of the truss rafter 10 as shown at 55 in FIG. 1.

The outer edges 51 and 52 of the respective boards 49 and 50 are provided with at least one recessed or notched areas or recesses are adapted to register in horizontal alignment and the inside edges thereof are adapted to lie in the same plane with the outer edge of the board 46. If desired, a plurality of notched or recessed areas

5 may be formed at the inner edges of the respective boards 49 and 50 and these notched recesses are likewise arranged in horizontal alignment with the innermost edges thereof in planar relation with the inwardly facing edge of board 46. Other recessed notches 60 and 61 may likewise be formed at the inwardly facing edges of the outer stud boards 49 and 50 as shown in FIG. 2, the horizontal alignment being preserved as previously described. The lowermost ends 62 and 63 of respective boards 49 and 50 are adapted to abut against the upper edges of the outer board laminations 37 and 38 of the floor joist 36 when the stud is placed in interconnecting relation between the truss rafter 10 and the floor joist 36. Again the stud member adjacent the lower end 48 of board 46 may be secured to the floor joist as by bolts 64 extending through the outer ends of the floor joist and through the lower depending end of the medial 2 x 4 member 46 in the interconnecting stud member 45. As previously pointed out, the stud member may be adhered with glue in laminated relation with the truss rafter and the floor joist if so desired, but it is preferred to maintain the frame unit in a partially knocked-down condition for shipment with the easy assemblage of the stud members through board members 64 and 55 to the respective floor joists 36 and truss rafter 10 as previously pointed out.

10 The stud member 45 which is disposed at the opposite side of the frame unit may have the identical parts formed with identical notch or recess areas and interconnected in the identical manner with the corresponding portions of the truss rafter and floor joist at the other side of the entire assembly. When the members are interfitted, it will be observed that the entire unit lies in substantially the same plane and that a rigid framing member is formed in which stress applied at any point 15 about the periphery of the unit will be transmitted to other portions of the rigid unit in a manner such as to assist in the distribution of stress applied to the completed building rather than allowing each separate structural portion to stand completely on its own merits without assistance from the other structural areas in the house construction.

20 In the actual building construction, I may employ a number of completed wooden frame units as above described, placing them at spaced parallel intervals, preferably 6 feet apart, to achieve a strong and cheap house construction. The end units are principally the same as the intermediate frame unit members and are preferably provided with a plurality of intermediate stud members which will give additional strength and provide support for such openings as windows and doors in the end of the housing. The end frame unit is indicated generally at 65 and has the same truss rafter construction as well as the same floor joist and stud construction as the frame units illustrated in FIG. 2. Additional studs or columns 25 66 may be provided between the truss rafter and the floor joist as shown in FIG. 1, appropriate notches or recesses being provided for interfitting the columns or studs therebetween. The columns 66 are preferably cut with a top edge 67 in horizontal alignment with one of the laminated members 68 of each of the columns 66 extending upwardly beyond the upper end 67 to engage the underside of the truss rafter and give additional support at the outer frame unit 65 as shown in FIG. 1. A brace 69 30 may extend across the entire end unit in abutting relation with the upper ends 67 of each of the columns 66 as shown, the brace 69 being glued or nailed in place as shown.

35 When a plurality of wooden frame units are mounted upon a foundation structure which may be continuous or may comprise individual blocks 70 as shown in FIG. 1, the blocks 70 first having been leveled each with the other, the frame units are maintained in their spaced parallel relation at the appropriate distance for separation while brace members 71 are placed across the units

in interfitting relation with respective outer edge notches or recesses 56, 57 and 58. The brace 71 is of such dimension as to tightly fit within the notches or recesses with the inwardly facing side of each of the braces in firm contact with the outwardly facing edge of the board 46 and with the innermost edges of the respective notches for attachment thereto. The dimension of the braces 71 is also selected with respect to its thickness such that the outwardly facing surface of each of the brace members will lie flush with the plane defined by the outwardly extending edges of the stud members 49 and 50. The braces 71 are preferably nailed into position so as to rigidly interconnect the spaced frame units and to rapidly construct the frame structure of a building.

Other brace members 72 may likewise be secured in interfitting relation with the recessed or notched areas 59, 60 and 61 of the stud members 45, the dimensions of the brace members being likewise selected so as to rigidly interfit and provide a flush surface with the inwardly facing edges of the stud members 45 in the same manner as the braces 71 cooperate with the outermost plane. It is understood that identical or similar braces for both the innermost plane and outermost plane at the opposite side of the building structure may be provided so as to form a nailing media in flush relation with the stud members as previously described.

When the frame members are mounted in the relationship disclosed, the upper edges of the individual truss rafters present a pair of pitched planes upon which roof boards 73 may be nailed or otherwise secured in the conventional manner. Finished roofing products may be applied in the usual manner to achieve a warm and tight roof. Floor boards preferably of 2 inch lumber are indicated at 74 and these may be secured to the floor joists 36 to provide a strong floor structure over which finish flooring may be applied in the conventional manner. Since each of the frame units at the medial portion of the structure is of the clear span type, the building construction will adapt itself to partitioning in an infinite number of positions without affecting the quality of the frame structure. The partitioning can add to the structural strength of the building if it is so desired, but in any event will not detract from the rigidity and strength which has been obtained through the special laminated construction and the special cooperation of the interconnecting braces with the studs at each of the frame units.

It may thus be seen that I have devised a novel building frame unit which provides a clear span between the truss rafter and floor joist in a vertical direction and between the opposed studs in a horizontal direction, the frame unit having a rigidity and simplicity such that the combination of only a few of such members when interconnected by flush brace members will provide a complete framing structure ready for application of internal and external sheet wall construction and the application of roofing and flooring to produce a high quality building structure. It will be noted that the clear span between the frame units in a horizontal direction may result in a situation where all of the structural members including the brace members, floor boards, sheathing and roof boards achieve their sole support from the frame units. The strength of the laminated floor joists coupled with the rigid frame construction obviates the necessity for additional floor joists as will be observed from the construction shown in FIG. 1.

It will, of course, be understood that various changes may be made in the form, details, arrangement and pro-

portions of the various parts without departing from the scope of my invention.

What is claimed is:

1. A self-contained wood framing unit comprising, a rigid closed frame having side-to-side laminated construction defining a floor joist, a truss rafter and interconnecting upstanding side studs, said side studs having at least one rectilinear board with straight parallel outer and inner edges, and having laminated thereto at least one rectilinear board having an edge in outwardly offset parallel relation to an edge of said first mentioned board and a notch formed thereacross and extending inwardly to the edge of said first mentioned board, whereby a transversely disposed brace may be fastened in said notch to the stud to provide therewith a flush nailing surface and a strong interconnection with an adjacent and similar framing unit.
2. The structure set forth in claim 1, wherein the laminated second mentioned rectilinear board has both side edges in outwardly offset parallel relation to the corresponding edges of the first mentioned board and notches are formed in opposed relation across the respective outwardly offset portions and extending inwardly to each of the respective edges of the first mentioned board.
3. A self-contained wood framing unit comprising, a rigid closed frame having side-to-side laminated construction defining a floor joist, a truss rafter and interconnecting upstanding side studs, said side studs having at least one rectilinear board with straight parallel outer and inner edges, and having laminated thereto at least one rectilinear board having an edge in outwardly offset parallel relation to an edge of said first mentioned board and a notch formed thereacross and extending inwardly to the edge of said first mentioned board, whereby a transversely disposed brace may be fastened in said notch to the stud to provide therewith a flush nailing surface and a strong interconnection with an adjacent and similar framing unit, said side studs also having a rectilinear board at the other side of the first mentioned rectilinear board having its respective edges in outwardly offset parallel relation to the edge of said first mentioned board and having a notch formed thereacross opposite said first mentioned notch and extending inwardly to the edge of said first mentioned board.
